(57) **CLAIM**

The ornamental design for shoe sole, as shown and described.

DESCRIPTION

FIG. 1 is a bottom perspective view of a shoe sole embodying the new design wherein an upper is shown in broken lines for environmental purposes only;

FIG. 2 is a bottom plan view thereof wherein an upper is shown in broken lines for environmental purposes only;

FIG. 3 is a front elevational view thereof;

FIG. 4 is a rear elevational view thereof;

FIG. 5 is a right side elevational view thereof wherein an upper is shown in broken lines for environmental purposes only; and,

FIG. 6 is a left side elevational view thereof wherein an upper is shown in broken lines for environmental purposes only.

FIGS. 1, 2, 5, and 6 show an upper and heel in broken lines for environmental purposes only. The upper and heel form no part of the claimed design.
